CLOTHESPIN

Hermann R. F. Stender, San Francisco, Calif.

Application June 10, 1946, Serial No. 675,515

1 Claim. (Cl. 24—137)

1

This invention relates to improvements in clothes pins.

The principal object of this invention is to provide a clothes pin wherein the clothes suspended thereby do not contact the supporting clothes line.

A further object is to produce a clothes pin wherein the clothes are tightly gripped and therefore cannot be pulled from the line by the wind or accidental contact therewith.

A still further object is to produce a clothes pin which is economical to manufacture, easy to use and one which will in no way injure materials or the clothes suspended thereby.

Other objects and advantages will be apparent during the course of the following description.

In the accompanying drawings forming a part of this specification and in which like numerals are employed to designate like parts throughout the same,

Fig. 1 is a front elevation of my pin as the same would appear in use.

Fig. 2 is a perspective view of the clamping wire.

Fig. 3 is a side elevation of my pin showing in full lines the first step in assembly, and in dotted lines the second step.

Fig. 4 is a side elevation showing the manner in which the pin is brought into engagement with the line, and

Fig. 5 is a cross sectional view on an enlarged scale taken on the line 5—5 of Fig 1.

In fastening clothes to a clothes line it has been customary to place the clothes over the line and to then secure them to the line by the pinching action of a so called clothes pin. With this procedure the clothes contact the line and are soiled by rubbing against the line, particularly during the whipping action caused by wind.

It is also true with the pinching type of clothes pin that the clothes may become detached from the line as the pin works loose.

I have, therefore, devised a clothes pin which obviates both of these difficulties.

In the accompanying drawings wherein for the purpose of illustration is shown a preferred embodiment of my invention the numeral 5 designates the body of my clothes pin which may be formed of any desirable material. This body is elongated as best shown in Figs. 1 and 3, and has its upper end bevelled as shown at 6, and is also provided, adjacent to the bevel, with a clothes line engaging recess 7. The bevel 6 extends from the upper end of the body 5 downwardly to the front side A of said body, the recess 7 extending from the side A and transverse the body 5.

2

At the lower end of the body 5 there is provided a forwardly projecting portion 8 between which and the main portion of the body is a transverse slot 10. The rear face B of the body 5 is provided with a transverse recess 10a located at a greater distance from the bottom end of the body than the slot 10. Extending vertically upward from the upper wall of the recess 10a is a slot 11, and extending left from the upper wall of the recess 10a is a second slot 12.

In addition to the body 5 there is provided a spring wire clip having one end bent to form a rectangular loop of a size to fit over the projection 8 with the bottom portion 13 of the loop fitting beneath the projection 8 and the upper portion 13a engaging in the slot 10. One side of the loop extends upwardly as at 13b and then transversely to provide a portion 15. From the portion 15 extends a side portion 14 rebent at its upper end as at 16 and from this rebent portion extends downwardly a second side portion 17 from the lower end of which extends a transverse portion 18 parallel to and spaced above the portion 15. The rebent portion 16 extends above the upper end of the body 5 and is bent backwardly as shown in Fig. 4. When assembled the wire member has the portion 13a fitted in the groove 10, the portion 15 fitted in the groove 12 and the portion 18 fitted in the groove 11.

At C is shown a clothes line and the clothes pin is applied to the line by bringing the convex side of the bend at 16 into contact with the line C¹, swinging the pin to bring the line into the position shown at C² and then pushing the pin upwardly so that the line engages the bevel, 35 springs the line across 14 and 17 away from the body 5 and thus allowing the line to engage in the recess 7 as at C.

To apply an article of clothes D to the pin the loop at the lower end of the wire is swung forwardly, an edge of such article is laid over the body part 8 and the loop allowed to spring back as in Fig. 5.

The movement of the line with respect to the clothes pin as a whole is indicated by the arrows of Figure 4.

It will thus be apparent that the pivotal action of the wire will cause the two horizontal portions of the wire 15 and 18 to effect a twisting or tensioning action on the upper end 16, thus placing 50 tension on the lever 14, which will in turn hold the line in the recess 7 and at the same time will hold the loop firmly against the clothes on the projection 8.

It is to be understood that the form of my invention herewith shown and described is to be

taken as a preferred example of the same and that various changes relative to the material, size, shape and arrangement of parts may be resorted to without departing from the spirit of the invention or the scope of the subjoined claim.

Having thus described my invention, I claim:

A clothes pin having a body of rectangular cross sections and having front and rear faces, said body having a bevelled upper end extending downwardly and forwardly from the rear to the front face, the body having a transverse recess in its upper front part below the bevelled end and having a transverse slot at its lower front portion defining a projection at the lower end, said body having a transverse recess at its lower rear portion more remote from the lower end of the body than said slot, said body having a transverse slot extending inwardly from said last recess and a second transverse slot extending upwardly from said last recess, and a spring wire member having a U-shaped upper portion including a pair of parallel portions terminating upwardly in a connecting portion and at their lower ends having transverse portions seated in the slots extending

from the second recess, said upper portion extending above the upper end of said body for engagement with a line held in said recess, said member having a portion extending downwardly from one of said transverse portions and terminating in a rectangular loop having an upper side engageable in the first mentioned slot and a lower side engageable beneath said projection at the lower end of the body.
